UNITED STATES PATENT OFFICE.

SAMUEL H. FISH, OF GLENDALE, CALIFORNIA.

LOCK MECHANISM FOR AUTOMOBILES.

1,250,575.

Specification of Letters Patent. Patented Dec. 18, 1917.

Application filed December 26, 1916. Serial No. 139,014.

To all whom it may concern:

Be it known that I, SAMUEL H. FISH, citizen of the United States, residing at Glendale, in the county of Los Angeles and 5 State of California, have invented a certain new and useful Improvement in Lock Mechanism for Automobiles, of which the following is a full, clear, concise, and exact description.

10 I have embodied my improvements in a structure that is especially adapted for securing the steering wheel of an automobile in the position to which it has been turned by the user, and at the same time clamping 15 the gas lever and the spark lever upon the sector arm, to hold the said levers out of use, and against possible interference therewith by unauthorized persons.

The object of my invention is to furnish 20 a clamping mechanism, in combination with a lock, so arranged, that when once in place, even a locksmith, without the special key, may not open the lock,—nor may the lock be broken by any ordinary means.

25 Speaking in somewhat general terms, my invention comprises a cone-shaped metal casing, which I cast preferably in two parts, and a loose ring, or annulus, fitted to the base of the said casing; the base of the casing 30 is provided with a socket, which is adapted to receive and secure the lugs of the clamping mechanism; the interior of the two castings which constitute the casing, are provided with openings, or spaces, to accommodate

35 the bolts, levers, plates, springs, studs and other members, which go to make up the interior, or working parts, of the lock. The annulus is provided with an inner collar, integral therewith, which bears against the

40 base of the casing on the upper side of said collar, while a disk, provided below and riveted or otherwise secured to the said base, comes against the under, or lower surface of said collar—and thus the annulus is se-

45 curely held, yet not prevented from being rotated. The tapered form of the casing, effectually prevents grasping the same by any ordinary monkey-wrench, while the loose ring fitted to the base as just described,

50 would prevent the effective use of a pipe-wrench to twist or break away the lugs or other parts. The loose ring is of sufficient width to form a rim below the outer edge of the base of the lock casing, and upon the

55 clamping mechanism is provided a seat for

said casing which comes within this lower rim, or edge, of the ring when the lock is applied to the clamp and the lugs thus inserted within the socket provided in the casting, or castings forming the lock casting, and thus the annulus is made to cover and protect the joint, or union, between the clamping mechanism and the cone shaped casing of the lock proper, thereby preventing access by means of a pinch-bar or similar tool,—such access being made more difficult by a flange which extends about the seat and immediately below the lower and outer edge of the annulus when in place.

The interior and working parts of my 70 lock, comprise lock bolts; bell-crank, or other suitable levers for operating the bolts; a plate, preferably placed between the key-operated arms of said levers; and studs, one or more, located radially within the path of 75 the bit or wing of the key,—which several parts may serve as wards and may be varied as to size, thickness, and relative positions among themselves to individualize different locks. It will be understood that springs 80 are connected with the lever mechanism and the parts so arranged that the lock bolts, placed opposite each other, are normally held by such spring pressure, to project into the socket, and the lugs when inserted, serve 85 to first wedge the bolts apart until the opening or eye of the lugs register with the bolts, whereupon the bolts actuated by the spring pressure will enter the said opening from opposite sides and the shackle will 90 then be securely held in place.

A key must be fitted to conform to each lock as individualized, so that on being inserted and turned the bolts will be withdrawn and held back, so that the lock may 95 be lifted from the lugs, and the clamping mechanism released.

My invention is illustrated in the accompanying drawing, in which:

Figure 1 is a front elevation of my automobile lock in position upon the shackle to hold the same clamped about any desired object.

Fig. 2 is a side elevation of the same, the position of the lock bolts in engagement with 105 the lugs being indicated by dotted lines.

Fig. 3 is a vertical, central sectional view of clamping mechanism, the lugs, the main casting, and the hinged bar, the seat for the lock casing, and the flange about said seat, 110

constituting such mechanism, being shown somewhat in detail.

Fig. 4 is a plan of the interior face of one of the castings of the lock case, the principal members of the locking mechanism being shown in place, the lugs, the annulus, and the disk upon which the collar of the annulus bears, being shown in section.

Fig. 5 is a sectional view, taken on line 16 5—5 of Fig. 4.

Fig. 6 is a general view, illustrating my invention applied to the steering wheel of an automobile.

Like parts are indicated by similar characters of reference throughout the several figures.

The lock casing is made up of two castings, the rear part *a* being formed on the face thereof to receive the operative parts 20 of the lock, which are shown mounted thereon. The companion casting *b*, of the same general contour, is shown as provided with the key-hole, and is constructed to fit over the operative parts of the lock, and when secured to its companion casting *a*, forms therewith the cone-shaped protecting casing of my invention.

When the parts are assembled, the disk plate *c* is secured to the base by rivets, or in 30 other suitable manner in the position shown, the outer portion of the disk plate, coming under and against the inner collar formed upon the annulus *d* serves as a seat and bearing therefor as most clearly illustrated in 35 Fig. 4, and the annulus or ring *d* is thus closely fitted about the base and serves to strengthen and protect the parts covered thereby, while at the same time the said ring is free to rotate, if a pipe wrench or similar 40 tool should be applied thereto.

The inclosing box *e* of the clamping mechanism is a casting, made to cover so far as may be, the parts to be guarded,—this particular form being made to fit the parts of 45 a particular car,—the form and construction may be varied as circumstances may require.

The lug *f* is made integral with the box *e*, and corresponds in form with its mate, lug *g*, provided on the free end of the hinged 50 bar, or shackle *h*. The disk shaped seat *i* as shown most clearly in Fig. 3, is formed upon the box *e*, and is provided with a flange *k*; and as indicated in Fig. 1 and Fig. 2 by dotted lines, this seat fits within the space 55 below the disk plate *c*, and the lower edge of the ring *d* surrounds and guards against access to the place between the seat and the disk or base of the cone shaped casing.

It will be observed that the lugs *f* and *g* 60 are cut away centrally, as shown in Fig. 3, and the ends of the bolts are made to correspond, so that when the socket of the lock is placed over the lugs, the ends of the bolts will be separated to admit the lugs, until 65 when the opening in the lugs registers with

the ends of the bolts, the bolts being under spring pressure, will enter from either side the opening in the lugs and thus the clamping box will be securely locked in place. These bolts *x* and *y* are in ways provided 70 therefor, and are connected with the lower arms *l* and *m*, respectively, of the bell-crank levers,—these levers being spring actuated; and the tension of the springs holds the levers, and consequently the said lock bolts, 75 normally in the position shown.

The plate *n* is placed preferably so as to come between the upper arms, which are acted upon by the key, and the studs *o* and *p* are placed radially at a short distance 80 from the key spindle, to be within the path or range of the bit of the key, the wing and bit of the key being shaped to fit the wards of its lock.

The upper flange of the ring *d* extends 85 upwardly upon the case above the bore which forms the ways for the lock bolts, thus concealing and protecting the ends of said bolts.

The levers, springs, plates, studs and 90 bolts being once assembled and in place, and adjusted to individualize the particular lock, are permanently inclosed. The inclosing case may be of steel or other metal castings, and in the form of the frustum of a cone, 95 and the loose, or rotatable ring is fitted about the base thereof as already described.

I prefer to rivet or otherwise permanently 100 secure the two parts *a* and *b* of the case together, and in like manner, rivet the disk *c* thereto, since it is entirely practical to depend on the key for opening the lock.

By varying the position, size, thickness, and the relative positions of the several parts of the lock, an indefinite number of 105 combinations may be obtained. It will also be understood that the form of the clamping box will be varied to various conditions.

In Fig. 6 I have shown the inclosing box *e* in position upon the steering wheel of an 110 automobile to hold the wheel in position, while clamping the gas lever which is shown at the right, and the spark lever not shown, to hold said levers out of active use and protect the same and other parts against possible interference by unauthorized persons.

Having thus described my invention I claim as new and desire to secure by Letters Patent:

1. The combination of the case in the 115 form of the frustum of a cone, a ring fitted about the base of the case, said ring being rotatable, and locking mechanism, contained within, and protected by said case.

2. The lock mechanism comprising bell- 120 crank levers, bolt devices operated by the lower arms of the levers, the upper arms thereof being adapted to be operated by a key, in combination with spring devices adapted to hold the bolt devices in position 125 130

for engagement, and a cone shaped case protecting the lock mechanism, a ring being provided upon the said case about the base thereof and capable of being rotated, to aid in such guarding of the said lock mechanism.

3. The metal case cast in two parts and secured together and forming the cone shaped protection for the key operated lock mechanism contained in said case, in combination with a loose ring upon the lower portion of the case, a disk secured to the bottom thereof, an interior collar provided on said ring bearing upon the said disk, the ring extending below said disk to form a rim, and the disk shaped seat of a clamping device fitting within said rim.

4. The lock mechanism comprising spring actuated levers, lock bolt devices controlled by said levers, in combination with a case in the form of the frustum of a cone and provided with a socket into which the bolt devices normally project, and clamping mechanism adapted to be engaged by said bolt devices, and a key for releasing the bolt devices by acting upon the said key operated arms.

5. The case in the form of the frustum of a cone provided with a socket, and engagement means of a lock inclosed in said case, in combination with clamping mechanism having shackle lugs adapted to be inserted into the socket to engage said lugs, the clamping mechanism being provided with a

disk shaped seat to fit within the rim which is provided about the base of the case.

6. The combination with the cone shaped case, of clamping mechanism provided with a seat fitting within a rim provided upon the base of the said case, a loose ring about the said base, the lower portion of said ring constituting the said rim, and a flange formed about said seat together with key operated locking mechanism contained within the case adapted to engage the clamping mechanism.

7. The lock mechanism comprising the case and a loose ring upon the base thereof, in combination with locking bolts in ways provided within the said case, and clamping mechanism having lugs adapted to be engaged by the bolts when inserted within a socket provided in said case.

8. The combination with the casing of the lock, of locking bolts carried in a bore provided in said casing, and a loose ring mounted on said casing and extending upwardly to cover the ends of said bore and thereby protect and conceal the said locking bolts.

In witness whereof I hereunto subscribe my name this 18th day of December, A. D. 1916.

SAMUEL H. FISH.
